Primary Examiner—Cathron Brooks(74) *Attorney, Agent, or Firm*—Jack J. Oney, Jr.; Ken K. Patel; Steven W. Miller(57) **CLAIM**

The ornamental design for a shelf display divider for absorbent articles, as shown and described.

DESCRIPTION

FIG. 1 is a bottom view of a first embodiment of a shelf display divider for absorbent articles, embodying our new design;

FIG. 2 is a left side elevational view thereof;

FIG. 3 is a right side elevational view thereof;

FIG. 4 is a top view thereof;

FIG. 5 is a front elevational view thereof;

FIG. 6 is a rear elevational view thereof;

FIG. 7 is a perspective view thereof;

FIG. 8 is a bottom view of a second embodiment of a shelf display divider for absorbent articles, wherein said apparatus has a coverplate to receive an insert card, embodying our new design;

FIG. 9 is a left side elevational view thereof;

FIG. 10 is a right side elevational view thereof;

FIG. 11 is a top view thereof;

FIG. 12 is a front elevational view thereof;

FIG. 13 is a rear elevational view thereof; and,

FIG. 14 is a perspective view thereof.
